CATCHUP DISPENSER

Jay G. Bain, Petoskey, Mich.

Application April 25, 1950, Serial No. 158,003

2 Claims. (Cl. 222—401)

1

This invention relates to new and useful improvements in dispensing attachments, and more particularly pertains to a dispenser incorporating an air pump for urging the dispensing of such viscous fluids as catchup.

The primary object of this invention is to enable a person to dispense viscous fluids such as catchup which are frequently difficult to dispense in the amount desired.

Another object of this invention is to provide a dispenser which will realize the foregoing objects and which may be used for an auxiliary function of agitating a viscous fluid to prevent the settling of the heavier components thereof.

Another object of this invention is to provide a dispenser of this character which may be efficiently operated, and which may be easily and swiftly attached to containers from which it is desired to dispense liquid.

Another object of this invention is to provide a device of this character which is simple and inexpensive in construction, yet which is durable and highly efficient for the purpose intended.

A meritorious feature of the present invention resides in the provision of a dispenser which constitutes a cap for the container and which is provided with a pouring spout.

Another important feature of the present invention resides in the provision of a dispenser in which the air pump portion thereof extends downwardly into the container to avoid any unsightly appearance of the same upon the container, as is common with devices of this character.

A final important feature to be specifically enumerated herein resides in the means provided for sealing the dispenser to the container and the means provided for securing the dispenser to the container.

These, together with various ancillary features and objects of the invention which will later become apparent as the following description proceeds, are attained by the present invention, a preferred embodiment of which has been illustrated by way of example only in the accompanying drawings, wherein:

Figure 1 is a perspective view showing the dispenser attached to a container from which the contents are being dispensed;

Figure 2 is a vertical transverse sectional view of the present invention showing the same attached to a container;

Figure 3 is a rear elevational view of the present invention showing the same attached to a container, and being taken at right angles to the view shown in Figure 2; and

Figure 4 is a fragmentary vertical sectional view of a modified form of the invention, in which different means are employed to secure the dispenser to a container, the container being shown in side elevation with portions broken away.

Reference is now made more specifically to the

accompanying drawings, wherein like numerals designate similar parts throughout the various views, and in which the dispenser is indicated generally by the numeral 10.

5 The dispenser 10 comprises a pump cylinder 12 which is closed at its upper end by an end wall 14. A piston 16 is reciprocably mounted in the cylinder 12 and a plunger rod 18 attached thereto and extending upwardly through the end wall 14 and terminating in a head portion 20. A compression spring 22 embraces the rod 18 and is seated between the head 20 and the end wall 14 so as to yieldingly urge the piston 16 to its uppermost position.

10 A conduit tube 24 having an enlarged upper end 26 received in and threadingly engaging the lower end of the cylinder 12 is provided, and the passage 28 within the tube 24 is enlarged within the portion 26, as at 30, to form a seat for the ball valve 32 which is normally retained in the seated position by a compression spring 34. The arrangement of the ball valve 32 and the spring 34 is such that only downward flow of air is permitted in the tube 24. It is to be noted that in order to facilitate the engagement or removal of the tube 24 from a cylinder, the portion of the tube 24 indicated at 36 is preferably provided with longitudinal ribs.

15 A jacket or housing 38 is provided for the cylinder 12, which, in the preferred construction, is integrally formed with the cylinder 12, and which merges at its upper end with the end wall 14. The jacket 38 is provided with a shoulder 40 against which a sealing ring 42 is seated. The jacket 38 is sufficiently spaced from the cylinder 12 so as to form a socket for the reception of the neck 44 of a container, indicated generally by the numeral 46, it being noted that the upper edge of the neck 44 is in engagement with the ring 42 and that the neck 44 is spaced from the cylinder 12 to provide communication between the interior of the container 46 and the outside atmosphere through a spout 48 formed in the jacket 38 adjacent the end wall 14.

20 One side wall of the cylinder 12 is thickened and is provided with a passage 50 communicating with the interior of the cylinder 12 at its lower end and the atmosphere adjacent the end wall 14. The passage 50 is provided with an enlarged portion in which is seated a check valve 52 which is normally retained in its closed position by a spring 54, the arrangement being such that air is permitted to flow into the cylinder 12 through the passage 50 but not outwardly therefrom.

25 As thus far described, it will be seen that downward pressure on the plunger rod 18 will cause air to be forced downwardly through the tube 24 into the interior of the container 46, and that upon release of downward pressure on the plunger rod 18, the cylinder 12 will be replenished by air drawn in through the passage 50 through the action of the spring 22, the upper portion of the

cylinder 12 being vented through the end wall 14 as at 56 to prevent interference with the action of the piston 16.

A pair of V-shaped members 58 are suitably pivoted at their apices to opposite sides of the jacket 38, as at 60, and the adjacent extremities of the members 58 are connected by clamping bars 62, to one of which is connected a finger latch 64 having a cam surface 66, the arrangement being such that the latch 64 may be pivoted into the position shown in Figure 2, whereby the latch 54 cooperates with the clamping bars 62 to engage the under side of an annular rib or bead 68 formed on the neck 44 of the container 46. It will be understood that the latch 64 may be pivoted to a position approximately ninety degrees from that shown in Figure 2 to release the clamping bar 62 from the rib 68, thereby freeing the dispenser 10 from the container 46.

In the modified form of the invention shown in Figure 4, the dispenser 10 is identical to the same shown in Figures 1-3 except in the manner by which the same is releasably secured to a container 46. Comparison of Figures 2 and 4 will show that in the latter the jacket 38, instead of terminating at the rib 68, flares outward at 70 at the rib 68 and extends downward therefrom in a depending annular flange 72. The flange 72 is provided with a plurality of radial, circumferentially spaced, threaded openings through which threadingly extend set screws 74 to engage the under side of the rib 68. It will be readily understood that the screws 74—three being the preferred number of the same—may be loosened to free the dispenser from the container 46, or tightened to secure the same thereon.

It will be noted that in the embodiment shown in Figures 1-3 the latch 64 tends to draw the sealing ring 42 into sealing engagement with the upper end of the neck 44 upon latching movement of the same; while in the embodiment shown in Figure 4, the screws 74 tend to serve the same purpose by cooperating with the curved surface of the rib 68 upon tightening of the same, so that in both embodiments cam means are utilized to effect both the sealing engagement and the securing of the dispenser and the container. It will be further noted, particularly with respect to the modification of Figure 4, that the jacket may be forced down upon the container neck to compress the resilient sealing ring in the event cam action is not desired, or the bead is not contoured properly.

It will be noted that in the preferred construction the tube 24 is slightly offset so as to be spaced slightly above the bottom of the container 46 at a position remote from the spout 48, so that when the dispenser 10 is in the position shown in Figure 1, action of the piston 16 will cause the formation of an air pocket at the uppermost portion of the container 46.

In the preferred construction, the jacket 38 is formed integrally with the cylinder 12 which may be conveniently made of plastic or corrosion resistant metal. While the tube 24 may be also constructed of plastic if desired, it will be obvious that the moving parts of the dispenser should preferably be metal.

From the foregoing, the construction and operation of the device will be readily understood and further explanation is believed to be unnecessary. However, since numerous modifications and changes will readily occur to those skilled in the art after a consideration of the foregoing specification and accompanying draw-

ings, it is not desired to limit the invention to the exact construction shown and described, but all suitable modifications and equivalents may be resorted to, falling within the scope of the appended claims.

Having described the invention, what is claimed as new is:

1. A catchup dispenser comprising a housing having a socket therein, a catchup container having its neck received in said socket in sealing engagement with the housing, said housing having a discharge spout communicating with the interior of said container, a pump cylinder carried by said housing and extending into the neck of the container, a piston reciprocably mounted in the cylinder and having a plunger rod attached thereto that extends upwardly slidably through said housing, air inlet means communicating between the interior of the cylinder adjacent its lower end and the exterior of the housing and a check valve therein, an elongated conduit connected to the lower end of the cylinder having a second check valve therein preventing flow into the cylinder through the conduit, said conduit extending to a position adjacent the bottom of the container, a shoulder formed in the wall defining said socket, sealing means seated between the shoulder and the upper edge of the container neck, an annular flange on the container neck, and means carried by the housing releasably engaging said flange for removably retaining said housing in engagement with said container.

2. In a dispensing device, a container having a neck which is provided with an annular bead intermediate its ends, a jacket removably embracing the container neck, manually operable means within the neck and carried by the jacket for pumping air into the container, said jacket having a dispensing opening therethrough, and means for urging movement of the jacket into and also for holding the same in sealing engagement with the container neck, said last means including a pair of V-shaped members the apices of which are pivoted to diametrically opposed sides of the jacket, clamping bars connecting the adjacent extremities of said members, a latch having a cam surface connected to one of the bars with the other bar and said latch releasably engaging said bead.
